UNITED STATES PATENT OFFICE

JAMES C. PETTIT, OF BLACKSTONE, VIRGINIA, ASSIGNOR OF ONE-THIRD TO CLAUDE MULLINAX AND ONE-THIRD TO BENHAM MORRISS, OF BLACKSTONE, VIRGINIA

SHUTTLE FOR SEPARATORS

Application filed November 8, 1929. Serial No. 405,798.

The present invention relates to a grain separator of the character illustrated and described in my Patents 1,609,188 and 1,722,943 and contemplates an improved construction of means for separating garlic, smut and other extraneous matter from the grain.

The invention provides a novel construction of means for the positive separation of all material lighter than the material to be cleaned, including immature grain, chaff, smut and weed seed.

The nature and advantages of the present invention will be better understood when the following detail description is read in connection with the accompanying drawings, the invention residing in the construction, combination and arrangement of parts as claimed.

In the drawings forming part of the application like numerals of reference indicate similar parts in the several views, and wherein:

Figure 1 is a fragmentary side elevation of the machine illustrating the present invention.

Figure 2 is a section view on line 2—2 of Figure 1.

Referring to the drawings in detail, 10 indicates generally a portion of the frame of the machine, on which is mounted an inclined chute 11, into which the garlic, grain and all other extraneous matter are deposited after being pressed in accordance with the disclosures of my patents above identified. The bottom of this chute includes a screen or foraminated portion 12 particularly located with reference to a pipe or casing 13 which rises above the frame of the machine as illustrated.

40 In other words the pipe or casing 13 is arranged directly above the chute 11 and in which a suction is created in any suitable manner. This suction is utilized to draw the extraneous matter from the grain as the latter passes through the chute 11. This extraneous matter clings to the shuttle screen 14 until it passes to the lower edge of the casing 13, whereupon the extraneous matter is removed from the screen by a rotary brush 45 15. It will be noted upon inspection of Fig-

ure 1 that the brush 15 is journaled in a suitable casing 16 and is located to engage the under surface of the screen 14 and thereby brushes or removes extraneous matter from the screen into a conveyor 17, also journaled within the casing 16. The conveyor 17 is of the spiral type, and consequently forces the garlic hulls and other extraneous matter longitudinally through the casing into an outlet or discharge spout 18 at one side of the machine. The spiral conveyor is rotated from any suitable source of power, the shaft of which being provided with a gear 19 which meshes with a similar gear carried by the shaft of the brush 15, so that the brush is simultaneously operated with the conveyor. The gear on the shaft of the brush is indicated at 20.

While any suitable means may be employed for the purpose of reciprocating the screen 14, I preferably employ a shaft 21 journaled in suitable brackets 22, and this shaft is rotated by a chain and sprocket indicated generally at 23. Carried by the opposed ends of this shaft are crank arms 24 to which are connected the corresponding extremities of operating rods 25, the latter having their outer ends connected with pins 26 projecting laterally from the screen frame 14.

While it is believed that from the foregoing description the nature and advantages of the invention will be readily apparent, I desire to have it understood that I do not limit myself to what is herein illustrated and described, and that such changes may be resorted to when desired, as fall within the scope of what is claimed.

What I claim is:

1. In a separator of the character described, an inclined chute having a foraminated portion in the bottom thereof, a suction casing arranged above said portion, an elongated reciprocatory screen frame mounted for longitudinal movement upon the chute and spaced above the bottom thereof, and against which the relatively light material is held by the suction created within the casing, means for reciprocating said screen, a casing adjacent one end of the chute, a rotatable brush mounted in said casing to remove said

material from the screen as it is shifted beyond said suction casing, and means arranged in the second mentioned casing for conveying the material from the chute after it has been 5 separated from the screen.

2. In a conveyor of the character described, an inclined chute having a foraminated portion in the bottom thereof, a suction casing arranged above said portion, a reciprocatory 10 screen frame mounted for longitudinal movement upon the chute and spaced above the bottom thereof, means for reciprocating the screen across the bottom of said suction casing, whereby the relatively light material is 15 held against the screen by the suction created within the casing, a casing arranged transversely of the chute and having an outlet spout, a brush journaled in the latter mentioned casing for removing the material from 20 the screen as the latter is shifted beyond the suction casing, a conveyor operating in the second mentioned casing for removing the material therefrom in the direction of said spout, and means for simultaneously operating 25 the brush from the conveyor.

3. In a conveyor of the character described, an inclined chute having a foraminated portion in the bottom thereof, a suction casing arranged above said portion, a reciprocatory screen frame mounted for longitudinal movement upon the chute and spaced 30 from the bottom thereof, a transverse shaft mounted for rotation, crank arms carried by the ends of said shaft, pins projecting laterally 35 from the sides of said screen frame, operating rods terminally connected with said crank arms and pins for reciprocating said frame across the bottom of said suction casing, whereby the relatively light material is 40 held against the screen by the suction created within the casing, a casing arranged transversely of the chute and having an outlet spout, a brush journaled in the latter mentioned casing for removing the material 45 therefrom in the direction of the spout, and means for simultaneously operating the brush and conveyor. 50

In testimony whereof I affix my signature.
JAMES C. PETTIT.
